CLAIM

The ornamental design for combined amplifier and speaker for portable hand held computer game, as shown and described.

DESCRIPTION

FIG. 1 is a top front side perspective view of a combined amplifier and speaker for portable hand held computer game showing my new design, the hand held computer game being shown in broken lines for illustrative purposes only and forms no part of the claimed design;

FIG. 2 is a top plan view thereof;

FIG. 3 is a front elevational view thereof;

FIG. 4 is a bottom plan view thereof;

FIG. 5 is a rear elevational view thereof;

FIG. 6 is a side elevational view thereof; and

FIG. 7 is a side elevational view thereof opposite that shown in FIG. 6.

FIG. 1

FIG. 2

FIG. 6

FIG. 3

FIG. 4

FIG. 7

FIG. 5
